UNITED STATES PATENT OFFICE

WILFRED A. FINNEGAN, OF BANGOR, MAINE

KNOCKDOWN HOLDER FOR CHRISTMAS TREES AND OTHER ARTICLES

Application filed May 29, 1929. Serial No. 366,831.

This invention relates to a knock-down holder adapted to be placed on a flat support and provided with a socket in which one end of an upright standard or member may be inserted, the holder being adapted to support the standard in a position perpendicular to the support, and composed of a plurality of duplicate arms, each so formed that it may be separably interlocked with another arm in such manner that the several arms may be assembled to form a socket and arm portions extending outwardly in different directions therefrom, to afford a stable support for an upright member inserted in the socket, the arms being separable from each other, so that the holder may be quickly erected for use and knocked down for storage and shipment.

A holder characterized as above stated is disclosed by my Patent No. 1,706,223, dated March 19, 1929, the arms being entirely of wood. The object of the present invention is to provide a holder of superior strength, durability and compactness, by making the arms entirely of sheet metal.

Of the accompanying drawings forming a part of this specification,—

Figure 1 is a perspective view of a holder embodying the invention.

Figure 2 is a top plan view of the holder, the outer ends of the arms being broken away.

Figures 3 and 4 are perspective views, showing portions of two arms separated from each other.

Figure 5 is an edge view of one of the arms looking toward its lower edge.

Figure 6 is a view similar to a portion of Figure 4, showing a modification.

The same reference characters indicate the same parts in all of the figures.

Each of the arms hereinafter described is a duplicate of the others, and is composed of a single piece of sheet metal, preferably steel, folded to form two sides 12 and 13, and a connecting neck 14, forming a stiffened longitudinal edge of the arm. Portions of the sides are spaced apart adjacent the inner end of the arm, to form a pocket 15 between the sides, and are preferably in close contact with each other elsewhere, so that the arm is suit-

ably reinforced and not liable to be easily bent. The side 12 has a transverse slot 15, which is narrower than the length of the pocket and constitutes a guideway permitting movement of the angular tongue next described, on the inner end of another arm, into and out of the pocket.

On the inner end of each arm is formed an angular tongue composed of a shank portion 17, and a laterally projecting web portion 18, said portions being movable respectively in the guideway 16 and pocket 15 of another arm, to interlock the arms, as indicated by Figure 2. Each angular tongue is preferably composed of two members, as shown by Figures 2, 3, 4 and 5, although, if desired, the tongue may be composed of a single member, as shown by Figure 6.

The pocket of each arm has a receiving mouth at its lower portion, formed by the lower edges of the sides 12 and 13, and may have another receiving mouth at its upper portion, formed by cutting away a portion of the neck 14, as indicated at 19, so that the tongues may enter the pockets and guideways, either at the lower or the upper edge of the arms.

The arrangement is such that the tongues and pockets of the several arms may be interlocked, as indicated by Figures 1 and 2, to form a holder adapted to have an extended bearing on a floor or other horizontal support, and including a socket 20 perpendicular to the support, and arm portions projecting outwardly in different directions from the socket.

The angular tongues are slidable into and out of the pockets and guideways, so that the holder may be quickly erected and knocked down and compactly stored.

When a Christmas tree trunk or other standard to be supported is inserted in the socket, any tendency of the standard to be inclined from a vertical position, causes the contacting faces of the angular tongues to bind on the sides of the pockets 15, and on the edges of the guideways 16, so that collapse of the erected holder is prevented, no means for positively connecting the arms with each other being required.

The portion of the side 13 of each arm

forming a side of the pocket 15, may be provided with a transverse stiffening boss 21, to prevent inward bending of said portion and accidental closing of the receiving mouth of the socket.

5 I claim:

1. A knock-down holder of the character stated, comprising a plurality of duplicate one piece sheet metal arms, each folded to form two sides and a connecting neck forming a stiffened longitudinal edge of the arm, portions of the sides of each arm being spaced apart to form a pocket between the sides adjacent the inner end of the arm, one of said portions being provided with a transverse slot forming a guideway communicating with the pocket, the inner end of each arm having an angular tongue formed to enter the pocket and guideway in another arm, the holder 10 formed by assembling the arms including a socket and arm portions projecting outwardly in different directions therefrom, the tongues being slidable into and out of the pockets and guideways, so that the holder 15 may be erected for use and knocked down for storage and shipment.
2. A knock-down holder as specified by claim 1, the neck of each arm being cut away adjacent the inner end of the arm, to form a 20 pocket mouth in the neck communicating with said pocket and guideway, so that the tongue of another arm may be inserted in the pocket and guideway and through the neck.
3. A knock-down holder as specified by claim 1, a side portion of each arm opposite the slot being provided with a transverse 25 stiffening boss.
4. A knock-down holder as specified by claim 1, the portions of the sides of each 30 arm at opposite ends of the pocket being in contact with and reinforcing each other.

In testimony whereof I have affixed my signature.

WILFRED A. FINNEGAN.
